METERING INSTRUMENT

George Banks, Emerson, N.J., and Michael Iannone, Farmingdale, N.Y., assignors to The Narda Microwave Corporation, Plainview, N.Y.

Filed Mar. 23, 1970, Ser. No. 22,000

Term of patent 14 years

Int. Cl. D10—10, 11

U.S. Cl. D52—6

FIG. 1 is a front view in elevation of a metering instrument showing our new design;

FIG. 2 is a side view in elevation thereof;

FIG. 3 is a top view thereof;

FIG. 4 is a bottom view thereof; and

FIG. 5 is a rear view in elevation thereof.

We claim:

The ornamental design for a metering instrument, as shown and described.
